UNITED STATES PATENT OFFICE.

JAMES W. PENFIELD, OF WILLOUGHBY, OHIO.

TILE-MACHINE.

SPECIFICATION forming part of Letters Patent No. 292,551, dated January 22, 1884.

Application filed February 6, 1883. (No model.)

To all whom it may concern:

Be it known that I, JAMES W. PENFIELD, of Willoughby, in the county of Lake and State of Ohio, have invented certain new and useful Improvements in Tile-Machines; and I do hereby declare the following to be a full, clear, and exact description of the invention, such as will enable others skilled in the art to which it pertains to make and use the same.

10 My invention relates to improvements in tile-machines; and it consists in certain features of construction and combinations of parts, hereinafter described, and pointed out in the claims.

15 The object of my invention is to perfect certain devices on which I obtained Letters Patent No. 98,519, in June, 1870, and to which reference is hereinafter made in this specification.

20 The improvements consist of the following, to wit:

First. A stop and a dog, by the operation of which the cutting device is carried along with the tile while the tile is being cut, so that the 25 cutting-wires bear the same relation to the tile as if the cutting were done while the tile remained at rest.

Second. The head of the machine supporting the molds is made with a bridge-tree firmly 30 attached to it for supporting the core of the molds. The head is provided with a seat, to which different-sized molds may be attached, and the parts so arranged that the molds and their cores will come into their relative positions without adjustment, the different-sized 35 cores being attached in turn to the same bar or bridge-tree.

Third. To the outer end of the molds are attached lubricators having a cavity surrounding the web of clay as it issues from the mold, into which steam, water, oil, or any lubricant 40 that is desired may be introduced. The outer end of the lubricator, being a trifle smaller than the mold gives, a finer finish to the product than otherwise attained.

45 Fourth. An improved cross-bar for supporting round tile on the cut-off table, and a new device for attaching them to the endless belt.

Fifth. An improved device for sanding and 50 giving a final finish to the product of the machine.

The machine to which my improvements, as well as my former patented devices, relate, although known to the trade as "tile-machines," are used quite as extensively for 55 making bricks. The distinction between tiles and bricks does not seem to be very clearly made, for the same product is sometimes called "tile" and sometimes called "brick," and they are usually made on the same machine 60 and of the same material. The most of my new devices are therefore equally well adapted to making either tile or brick.

In the drawings, Figure 1 is a side elevation of that portion of the machine usually called the "cut-off" table, showing some of my new devices. Fig. 2 is a cross-section taken on the line *x x* of Fig. 1. Fig. 3 is a transverse sectional view, showing my new device for holding the molds and cores. Fig. 4 shows a new 70 device for a dog for coupling the cutting device with the endless belt. Fig. 5 shows a stop for gaging the length of tile, and also for carrying along together the tile and the cutting device while the cutting is performed. Fig. 6 is a view in perspective of my new cross-bar. Fig. 7 is a vertical cross-section taken on the line *y y* of Fig. 1. Figs. 8 and 9 illustrate 75 my new device for attaching the cross-bars to the endless belt. Fig. 10 is a view in perspective of my new lubricator. Fig. 11 is a vertical longitudinal sectional view of the same.

A represents the frame of a cut-off table provided with rollers journaled in the side pieces 85 of the frame, and supporting the endless belt B, to which are attached the cross-bars C.

D represents a frame supporting the cut-off wires, and is attached to the rod *d*, as is also the stop D' and the dog D'', the said rod being 90 supported in suitable bearings extending from the frame A. The frame D, the stop D', and the dog D'' are preferably so attached to the rod *d* that they can each turn on the said rod, but can only move endwise, as the rod moves 95 endwise, and therefore the frame, stop, and dog will all move endwise together. The said frame, stop, and dog have each a pin, *d'*, *d''*, and *d'''*, respectively, projecting below the rod *d*, and that strike against the frame A when 100 these respective parts are raised to desired position, and hold these parts from falling over.

backward. The pin d' has also a pin extending laterally across the pin d^2 in such a manner that when the frame D is drawn forward slightly it will let the front end of the dog fall 5 and engage the cross-bars on the endless belt, where it will remain until the said frame is again raised almost to its vertical position. The stop D' should be placed the same distance from the wire that is next to it that these 10 wires are apart on the frame D, so that when cut the piece next the stop D' will be of the same length as the pieces that are between the wires.

The operation of this part of the device is 15 as follows: When the tile first issues from the mold, the end thereof will be uneven and will require to be cut off at the point where the product first becomes perfect. For this purpose the product is allowed to pass along the 20 table until the point where it is desired to sever it comes opposite one of the severing-wires. The severing or cutting of the product is done by drawing down the frame D and pressing the cutting-wires through the 25 product; but as soon as the said frame is drawn forward, and before the wires engage the product, the dog D² is allowed to drop between the cross-bars, and this carries the cutting device along with product while the cutting 30 is done. At the next cutting the product is allowed to approach the stop D', when the said stop is drawn down, so that the product butts against it. This carries along the cutting device, as before described, and the 35 severing is accomplished. After each cutting the parts are pushed back into their first position.

Different arrangements of these devices may be had to accomplish the same end. For example, instead of the rod d moving endwise, the frame D, the stop D', and the dog D² might be coupled together by a sleeve or otherwise, and slide on the rod d ; or the said frame, stop, and dog might all be hinged to the frame 45 A, and this frame made to move forward on the rolls a . Heretofore each mold and its core had a bar firmly attached to them across on the inside of the machine, to hold the core in a central position in the mold, and every 50 time that the molds had to be changed it was necessary to dig said bar out of the clay, in which it would be firmly embedded. Also, the first cost of making so many bars was considerable. My new device, as shown in Fig. 55 3, is intended to correct these defects.

F represents the sides of the chamber through which the clay is forced to the molds. f is the bridge-tree, supporting the core f², by means of the bolt f'. The said bridge-tree is firmly 60 attached to the head G, which in turn is securely bolted to the flanges on the sides F. The head G is provided with a seat, the outside shoulder of which is at g', and the flanges of all of the different sizes of molds are made 65 of such diameter as to nicely fit the shoulder g' of the said seat. Also, the bolt f' being

made central with the said seat and the shoulder g', and the cores all having been provided with a central hole to fit the said bolt, it will be seen that the molds and cores may be 70 changed with but little trouble, and without changing or displacing any other part, and that but one bridge-tree is required for any number of molds and their respective cores.

In some cases it is desirable to have what 75 might be called a "supplemental treatment" of the product after it has passed the mold. For this purpose I have invented what I call a "lubricator," H, which is attached to the mold in a manner as shown in Figs. 10 and 11, 80 the essential parts being the chamber h, into which steam, oil, water, or any desired lubricant may be introduced, and the mouth h', that is made of like shape as the molds, but may be made a trifle smaller, so that it may 85 rub on the surface of the product. The said rubbing, in combination with lubricant used as aforesaid, will give a much better finish to the surface of the product than it had when it issued from the molds.

Some of the products of the machine—such as roofing-tiles, paving-tiles, and some kinds of bricks—are greatly improved by a dressing of sand applied to their faces, sides, and edges. For this purpose I have invented a device, a 95 side view of which is shown in Fig. 1 and an end view in Fig. 6. This portion of it consists of a frame, a', supporting rollers that are journaled in the side pieces thereof and over which passes an endless belt, b, all supported in such 100 a manner from the frame A, that the belt b shall press on top of the product and be carried along thereby, and made to pass around its rollers. The side pieces, a', are hinged to the frame A in such a manner that the top of 105 them can be let down until the said side pieces, a', are in a horizontal position. The sides a' are raised or lowered by the rods e, that are operated by arms e', from the roller E, that in turn is operated from the treadle a².

E' represents the end of the bar of clay as it issues from the machine in shape to be cut into paving-tiles. The operation of this part of the device is as follows: The side boards, a', having first been let down, sand is scattered 115 over them and the top of the endless belt b. The boards, by means of the operator's foot on the treadle e', are brought to their upright position against the web of clay E. The said web of clay being in motion, the sand from 120 the belt b is rolled onto the top of the web, while the sand on the boards a' is rubbed into the sides of the said web of clay.

If so desired, a board might be hinged to take the place of the rollers and belt b and 125 operated and raised by the treadle e', so that sand could be thrown under the board on the top of the web of clay, when the board, again closing down, would rub the sand into the top of the web of clay instead of rolling it in, as 130 with the rollers and belt.

In all cases where the product of the machine

is in rectilinear form—such as paving-tile, roofing-tile, bricks, and the like, or in a variety of other forms where one side or one portion of the product is flat—the endless belt 5 B is used without the cross-bars, the product coming directly from the molds onto the said belt. It is found better to support a round tile not directly on the bottom but at two points a short distance each side of the bottom point. My improved cross-bar C for this purpose is shown in Fig. 6. To the high points a at the ends of the bar and to the central portion of the bottom b, is fastened a belt, upholstered band, web, or any such suitable 10 device in such a manner that round tile will be supported, as aforesaid, without touching the said bottom point. This kind of cross-bar, in addition to its supporting the tile in the best possible manner, has this advantage, that it 15 will operate on several different sizes of tiles.

In Figs. 8 and 9 is shown my new device for attaching the cross-bars to the endless belt. Heretofore, if both edges of the cross-bar were fastened to the belt, the belt would not run 20 smoothly around the rollers at the end of the frame, and beside the fastenings were liable to tear out. If, however, but one edge of the cross-bar is fastened, it is liable to be tilted edgewise and mar the tile.

30 My improvement consists in attaching firmly to each end of the cross-bars a strip of sheet metal, and attaching the other end of the strips to the endless belt, the manner of which is clearly shown in the drawings. This makes 35 so broad a surface on the belt that the bar cannot tilt. It does not interfere with the belt running smoothly around the pulleys, and also insures the cross-bar coming up with the flat surface (and not cornerwise) against 40 the bottom of the tile.

I have discovered that rubber belt with one side of it made of canton-flannel or some similar material with the woolly side out is an article of great value of which to make the bands, 45 (shown in Figs. 4 and 6,) and also of which to make the endless belt B. The rubber belt is impervious to moisture and is therefore durable and is at all times of equal flexibility, while by adding the canton-flannel or its equivalent 50 the surface becomes more soft and yielding, and also is so porous that a vacuum will not

form between the clay and the belt. Therefore the clay will not adhere to the belt.

In case it is desired, a sieve might be suspended over the sanding device and operated 55 automatically from the treadle e² for the purpose of scattering the sand as required, instead of scattering the sand by the hand.

What I claim is—

1. In a tile-machine, the combination, with 60 the cutter and an endless carrier, of a pivoted gravity-dog adapted to engage the cross-bars of the endless carrier and cause the cutter to be carried along with the endless carrier, substantially as set forth.

2. In a tile-machine, the combination, with 70 the cutter and an endless carrier, of a pivoted gravity-dog adapted to engage the cross-bars of the carrier, and devices connecting the cutter and dog, whereby the cutter, when moved forward, will release the dog and cause it to engage the endless carrier and cause the cutter to be carried along with the endless carrier, substantially as set forth.

3. In a tile-machine, the combination, with 75 an endless carrier, of a stop constructed and arranged independent of the carrier and adapted to be adjusted to allow the end of the cut product to come in contact therewith and to carry the cutting device along with the carrier, 80 substantially as set forth.

4. In a tile-machine, the combination, with 85 the endless carriers, of an endless belt for sanding one face, and hinged side pieces for sanding the edges, substantially as set forth.

5. In a tile-machine, metal strips, by means of which the cross-bars are fastened to the endless belt, substantially as shown and described.

6. The combination, with the cut-off table, 90 of rubber belting with one surface made of canton-flannel or its equivalent with the rough side out, substantially as and for the purpose shown and described.

In testimony whereof I sign this specification, 95 in the presence of two witnesses, this 25th day of January, 1883.

JAMES W. PENFIELD.
